UNITED STATES PATENT OFFICE.

JAMES F. WALLACE, OF ROCHESTER, NEW YORK, ASSIGNOR TO CERTO CORPORATION, OF ROCHESTER, NEW YORK, A CORPORATION OF NEW YORK.

MERCHANDISE PACKAGE.

Application filed March 24, 1927. Serial No. 178,100.

The subject matter of this application is a continuation in part of the subject matter of the co-pending application 84,996 filed Jan. 30, 1926.

5 This invention relates to merchandise packages, and particularly to those comprising a bottle with which the manufacturer desires to furnish a recipe booklet. One object of this invention is to provide an improved package 10 in which an instruction or recipe booklet is applied directly to the bottle to form therewith a complete and self-contained package so that such a booklet is always supplied the user in convenient form with every bottle; 15 with which the booklet is confined to the bottle in such a manner that it is protected from injury in handling before reaching the consumer; with which the booklet may be readily separated from the bottle by the consumer 20 without causing any damage to the booklet; and with which the bottle permanently carries a proper label even after the booklet is separated therefrom.

A further object is to provide an improved 25 package comprising a bottle and a booklet, which may be economically assembled in automatic machines with uniformity in the relationship of the booklet and bottle, and with a minimum of loss by damage to the booklet 30 and a minimum of operations in the machines.

A further object is to provide a simple, inexpensive and convenient package of this 35 type in which the booklet is substantially concealed so that it presents the neat and attractive appearance of a bottle labeled in the ordinary way.

Other objects and advantages will be apparent from the following description of the 40 invention, and the novel features will be particularly pointed out hereinafter in connection with the appended claims.

In the accompanying drawings:

45 Figure 1 is a front elevation of a bottle embodying the present invention;

Figure 2 is a side elevation of the same partly broken away;

Figure 3 is a similar side elevation largely in section;

4a—4^a Figure 4 is a sectional plan view on the line

Figure 5 is a perspective view of a retainer for the booklet forming a part of the package;

55 Figure 6 is a perspective view of the booklet detached, and

Figure 7 is a perspective view showing the booklet encased in the retainer and provided with a band for securing the same as a unit to the bottle.

60 Similar reference numerals throughout the several views indicate the same parts.

The embodiment of the invention herein disclosed by way of illustration, comprises a 65 bottle 10, in a side of which a depressed area or panel 11 is formed by moulding the depression therein during manufacture of the bottle. The dimensions of this panel preferably correspond to the thickness, length and width of a recipe or instruction booklet after 70 the latter has been prepared for application to the bottle. In the case of round bottles, this panel preferably extends not more than approximately half-way around the bottle, as 75 shown in Figure 4.

A suitable booklet 12 containing recipes or instructions for the use of the contents of the package or bottle is preferably prepared in a folded, compact form and held in such form by an open ended retainer or jacket 13, shown in Figures 5 and 7. This jacket comprises a simple strip of paper as wide as the vertical dimensions of the booklet as applied to the panel, and long enough to completely enfold the prepared booklet and for the ends 85 of the jacket to lap over and be pasted together as at 14, Figure 5, but not to the booklet. Such a jacket may be economically assembled on the booklet by machines, on a 90 large scale.

95 In the case of round bottles, such as shown in the drawings, and where the booklet is of such size as to require folding, it should be folded and bound so as to open at the end of the paging rather than at the side of the same, as best shown in Figure 6 where the 100 pages are shown as folded from side to side and bound together at 15, and again folded in the same manner at 16 to reduce the size 105 of the booklet. The jacket 13 is applied to the booklet so that the open ends of the jacket lie along the sides of the pages and the folded ends of the jacket lie along the bound and folded portions of the booklet as illustrated in Figure 7. The jacketed booklet thus assembled is placed in the panel 11 of the bottle so that the folded portions of the jacket and booklet extend in a straight line along the

longitudinal or vertical sides of the panel, as shown in Figure 4. This advantageous arrangement allows the jacketed booklet to easily conform to the curved surface of the panel with a minimum of flexing, so that the jacketed booklet hugs the surface of the bottle closely and smoothly, and permits of the use of a booklet of substantial proportions, in the present instance, for example, one of 10 about forty pages. It will be understood however, that the term booklet is used in a broad sense as inclusive of folded sheets, pamphlets, booklets and the like generally, of a greater or less size and of different specific forms.

The jacketed booklet is preferably secured to the bottle in the position described, either by applying to the jacket one or more lines 17 of a suitable adhesive, to secure the jacket 20 directly to the face of the bottle panel, or by applying a strip of paper 18 across the panel after the jacketed booklet has been inserted, the ends of the paper strip being glued to the surface of the bottle beyond the sides of the 25 panel, and preferably overlapping with each other as indicated in Figure 7.

The jacketed booklet thus secured in panel 11 by one or another of the above methods is then further confined therein, protected 30 and concealed by a label 19 of the same vertical width as the panel and which preferably extends around the bottle with its ends lapped beyond the sides of the panel as at 35 19, Figure 4. The label is secured to the bottle by the application of paste over a substantial portion of the area of the label which covers the plain face of the bottle beyond the sides of the panel. Preferably the design and printed matter of the label is applied 40 thereto on the portion covering and permanently attached to the plain surface of the bottle beyond the sides of the panel as indicated at 20, and the same or other designs or printed matter may be applied to the label 45 upon the portion covering the depressed area and booklet, as indicated at 21, Figure 2. Since the label completely covers and confines the booklet, no corner or other portions of the latter can project to be caught and 50 torn or detached by contact with other containers or articles.

The label 19 may be transversely weakened, as by a line of scoring or perforations 22 extending over the depressed area or panel to 55 facilitate the breaking of the label by the consumer when the removal of the booklet is desired. This weakened or perforated line is preferably located along each vertical edge of the panel for the reason that the groove or channel between the booklet and the adjacent edge of the panel leaves the label unsupported at this portion so that it may be readily broken to remove the booklet by the finger nail, or any suitable implement. The bottle 60 may also have a shoulder means or depre-

sion 23 in its bottom wall for cooperation 70 with a machine part to aid in properly centering, facing and handling the bottle in machines for assembling the jacketed booklet, bottle and label.

The jacketed booklet is preferably applied to the bottle by automatic machines and the retainer or jacket 13 serves to keep the booklet from unfolding and allows it to be readily handled as a closed and compact unit in such machines. The bottle with the jacketed booklet secured as described in the panel is then handled as a single unit in the automatic machines by which the label is placed and secured on the bottle without any interference whatever with the operation of such machine.

It is impracticable to adhesively secure an unjacketed booklet directly to the surface of the panel for the reason that it could not then be handled in automatic machinery without unfolding and being injured or torn off, and for the further reason that it would be injured when removed by the consumer, but by the use of the jacket 13, the booklet may not only be handled in the machine as a compact unit, but may be removed without injury by merely breaking the label over the channels at the edge of the booklet and tearing the paper jacket, thus producing the booklet, detached, in a clean and fresh condition.

Inasmuch as the label entirely surrounds the bottle with its ends overlapping and secured to one another, as well as to the plain portion of the bottle, the jacketed booklet cannot become loosened from the container and lost before the bottle reaches the consumer. When the label is broken in order to remove the booklet, the portion of the label covering and secured to the undepressed or plain area of the bottle will remain adhesively connected to the latter and will thus continue to display information relative to and identifying the product. Thus it is necessary to apply but a single label to the product.

Since the label is of substantially the same width in a vertical direction as the panel and the portion of the label over the panel is flush with the portion thereof over the rest of the bottle, the label not only serves to completely confine the booklet in the panel, but also effectively conceals the panel and booklet. The bottle therefore occupies the same space and may be handled with the same freedom and celerity as an ordinary bottle and furthermore presents the outward form and adaptability and the neat and finished appearance of an ordinary bottle labeled in the ordinary way. The label is left fully displayed and its appearance is in nowise marred by the substantial recipe book securely carried beneath it, which would not be observed except for printed directions on the face of the label informing the consumer of the pres-

ence of the booklet and giving instructions for its removal.

The invention thus provides, among others, the important practical advantages of a bottle which inevitably carries an undamaged and substantial recipe booklet to every consumer; which at the same time affords the same undiminished opportunity for display in store windows and on store shelves and counters as in the case of a bottle labeled in the ordinary manner, and which also retains a permanent label even after the booklet of instructions is removed.

It will be obvious that various changes in the details herein described and illustrated by way of explanation of the invention may be made by those skilled in the art within the principle of the invention, as set forth in the appended claims.

20 I claim as my invention:

1. A merchandise package comprising a container having a depressed panel in a face thereof, an instruction booklet disposed and housed in said panel, means securing said booklet in said panel to adapt said booklet and container for convenient manipulation together as a unit in labeling operations, and a label having a vertical width over said panel substantially equal to that of said panel and encircling said container to enclose and conceal said booklet and present the outward form, adaptability and appearance of an ordinary container labeled in the ordinary manner.

35 2. A merchandise package comprising a container having a depressed panel in a face thereof, an instruction booklet disposed and housed in said panel, means comprising a retainer secured around said booklet for holding the same compactly closed and secured to the container in said panel to adapt said booklet and container for convenient manipulation together as a unit in labeling operations and a label secured to said container at

45 opposite sides of said panel and extending

thereacross and having a vertical width substantially equal to that of said panel to enclose the same and said booklet.

3. A merchandise package comprising a container having a depressed panel in a face thereof, an instruction booklet disposed and housed in said panel, means comprising a retainer secured around said booklet for holding the same compactly closed and secured to the container in said panel to adapt said booklet and container for convenient manipulation together as a unit in labeling operations and a label secured to and encircling said container with a vertical width over said panel substantially equal to that of the latter to enclose said panel and booklet and to provide a label portion permanently attached to the container opposite said panel for the reception of printed matter, said label having a line of weakening adjacent a side of said panel for removal of said booklet in intact condition.

4. A merchandise package comprising a container having a depressed panel in a face thereof, an instruction booklet disposed and housed in said panel, means comprising a retainer secured around said booklet for holding the same compactly closed and secured to the container in said panel to adapt said booklet and container for convenient manipulation together as a unit in labeling operations, a label secured to and encircling said container with a vertical width over said panel substantially equal to that of the latter to enclose said panel and booklet and to provide a label portion permanently attached to the container opposite said panel for the reception of printed matter, said label having a line of weakening adjacent the same for removal of said booklet in intact condition and shoulder means on said container in predetermined relation to said panel for centering the container preliminary to the application of said label.

JAMES F. WALLACE.
